UNITED STATES PATENT OFFICE.

THOMAS R. PADGETT, OF GAFFNEY, SOUTH CAROLINA.

PLAITING DEVICE.

Application filed November 5, 1925. Serial No. 67,028.

This invention relates to means for forming plaits in cloth or the like, such, for example, as are used in the making of apparel.

5 The object of the invention is to provide a simple and efficient device which can be used in connection with an ordinary pressing table or ironing board for rapidly and accurately making either box or knife plaits, as desired.

In order that the invention may be readily understood, reference is had to the accompanying drawings, forming part of this specification, and in which:—

15 Figure 1 is a plan view of my improved device, showing the same in position on an ironing board;

Figure 2 is a side elevation thereof;

20 Figure 3 is a transverse section substantially on the line 3—3 of Figure 1;

Figure 4 is a similar and fragmentary section on an enlarged scale illustrating the parts in a different position;

25 Figure 5 is a similar fragmentary view on a still further enlarged scale showing some of the details of construction;

Figure 6 is a plan view on an enlarged scale of one of the detents shown in Figures 1 and 2;

30 Figure 7 is a longitudinal section thereof on the lines 7—7 of Figure 6; and

Figure 8 is a fragmentary end elevation of the device shown in Figures 1 and 2.

35 Referring to the drawings in detail, my improved device comprises a rectangular frame formed of side members 1 and 2, end members 3 and 4, and cross members 5 and 6, arranged adjacent the end members.

40 To a pair of strips or bars 7 and 8 are secured the side edges of a flexible sheet or base 11, preferably formed of textile material and this sheet is stretched over the frame by means of clips 9 and 10 which are secured to the strips 7 and 8 and engage under the side members 1 and 2 of the frame as best shown in Figure 3. It will be understood that the frame is made of such a size as to snugly fit over and enclose an ironing board X or the like, so that the upper surface of this board is substantially flush with the top of the frame, and the sheet or base 11 is supported on the board in a horizontal position.

45 Carried by the flexible sheet or base 11 are a series of horizontal parallel upstanding fins or ribs 14, as shown in Figure 3. These

fins or ribs extend the full length of the sheet 11 and are spaced apart a distance approximately equal to their height.

50 By reference to Figure 5, it will be seen that each fin or rib comprises a thin, relatively rigid strip 12, of metal, wood, whalebone or the like, with the sheet 11 looped over such strip and stitched together along the lower edge of the strip, as indicated at 55 13. This line of stitching therefore constitutes a hinge about which the upstanding fin may be turned in either direction so as to lie substantially flat upon the sheet 11, as indicated in dotted lines in Figure 5 and at 70 the right hand side of Figure 4.

55 The end member 3 of the frame shown in Figure 1 is removable, being held in the side members 1 and 2 by means of notches 3^a (see Figure 2). Secured to this removable 75 end member are a series of strands or small wires 15. These wires are spaced apart a distance substantially equal to that between the fins and may be held in such spaced relation by means of notches formed in the upper surface of the cross bar 5, as shown.

60 These strands or wires extend longitudinally of the sheet 11 and are secured at their other ends to a series of levers 16. Each of these levers is preferably provided with a flat- 80 tened end 16^a and is pivotally mounted at its other end on a shaft 17 supported in brackets 19, secured to the frame. Spacing sleeves 18 are preferably interposed between the levers 16, as shown in Figure 8, so as to 85 space them uniformly along the shaft.

65 The upper edge of each lever is preferably serrated to provide ratchet teeth and cooperating with these teeth is a swinging detent or pawl 20, pivotally supported on 90 a rod 21 secured to the end member 4 of the frame. By reference to Figures 6 and 7, it will be seen that I preferably provide each detent with a struck-up portion 20^a, adjacent its pivot, such portion forming a finger hold by means of which the detent may be operated. The struck-up portion 20^a is preferably formed with an opening 20^b through which the wire or strand 15 may pass.

70 From the above, it is obvious that by pressing down upon the flat ends of the levers 16, the wires or strands 15 may be individually stretched or tensioned and may be maintained under tension by means of 110 the pawls 20. When it is desired to release the wires, the levers are slightly de-

pressed so as to permit the pawls 20 to be disengaged therefrom, and the levers may then swing freely on their pivots. After the tension is relieved in this manner, enough slack is provided in the strands to permit the end member 3 to be disengaged from the notches 3^a and bodily removed, so that the whole series of wires may be lifted from the base or sheet 11.

10. In operation, the plaiting apparatus having been first mounted on an ironing board, as shown, the cloth or other material to be plaited is laid or spread over the plaiting device so that it rests upon the upper edges 15 of the fins 14. The series of wires are then positioned over the cloth in such a manner that each wire enters the space or groove between two fins, thus forcing the cloth or fabric to be plaited down between the fins. 20 Preferably the wires are so positioned that each one lies closely adjacent the lower edge of a fin, as shown in Figures 4 and 5. After the wires have been so positioned, and the end bar 3 put in place, the wires are tightened to the desired extent by depressing the levers 16, as described. At the left of Figure 4 and in Figure 5 is shown how the material to be plaited appears after the wires or strands have been placed in position. The material is indicated at Y and by reference to Figure 5, it will be seen that this material is drawn snugly down along the side of one fin where it passes under the wire and thence up and over the next adjacent fin.

The material to be plaited having been placed on the plaiting device, as above described, it is obvious that the fins may be swung about their lower edges down into 40 a horizontal position as indicated at the right of Figure 4, the fins carrying the material with them and causing it to be stretched smoothly over and under each fin, as shown. If now a hot iron be passed over the flat lying fins and material, it is obvious that uniform and accurate creases or folds will be made in the material at the edges of the fins, thus producing plaits. As

shown in Figure 4, knife plaits would be produced, but if the fins are folded down alternately in opposite directions, box plaits would result.

After the pressing operation, the wires are released, as described, and lifted from the material, and after this, the material may be readily removed from the device.

What I claim is:—

1. A plaiting device comprising a series of fins or ribs hingedly attached along one longitudinal edge to a support, a series of strands, and means for stretching said strands over the support between and parallel with said fins or ribs.

2. A plaiting device comprising a flexible base, a series of fins or ribs hingedly attached along one longitudinal edge to said base, a frame to which said flexible base is attached, a series of strands secured to said frame, and adapted to be positioned parallel with and between said fins, and means for tensioning said strands.

3. A plaiting device comprising a flexible base, a series of fins or ribs each comprising a relatively rigid strip having the material of the flexible base looped therearound and stitched along one longitudinal edge, the line of stitching constituting a hinge about which said fin can be swung in either direction into substantial contact with the base, a series of strands, and means for so positioning said strands that they may be stretched over said base in the spaces between said fins.

4. The combination with an ironing board or the like, of a series of parallel normally upstanding fins or ribs supported thereby, said fins being hinged along their lower edge and capable of folding over into a flat, horizontal position, and a series of strands also supported by said board and arranged to be stretched over the board between and parallel with said fins.

In testimony whereof I affix my signature.

THOMAS R. PADGETT.
